Primary Examiner—Stella Reid

[57] CLAIM

The ornamental design for a combined ring and copper alloy coil spring to cure athlete's foot, as shown and described.

DESCRIPTION

FIG. 1 is a perspective top view of a combined ring and copper alloy coil spring to cure athlete's foot, showing my new design;

FIG. 2 is a top plan view thereof;

FIG. 3 is a bottom plan view thereof;

FIG. 4 is a front elevation view thereof;

FIG. 5 is a longitudinal cross sectional view thereof, taking along lines 5—5 of FIG. 2; and,

FIG. 6 is a top plan view thereof, in position of use on a foot, which is shown in broken lines for illustrative purpose and forming no part of the claimed design.
